UNITED STATES PATENT OFFICE.

JACOB B. BEAM, OF PUNXSUTAWNEY, PENNSYLVANIA.

AUTOMOBILE RADIATOR.

1,409,273.

Specification of Letters Patent. Patented Mar. 14, 1922.

Application filed August 17, 1918. Serial No. 250,396.

To all whom it may concern:

Be it known that I, JACOB B. BEAM, a citizen of the United States, residing at Punxsutawney, in the county of Jefferson 5 and State of Pennsylvania, have invented new and useful Improvements in Automobile Radiators, of which the following is a specification.

This invention relates to radiators for 10 use in connection with the cooling system of internal combustion engines.

The primary object of the invention is to provide a radiator having a casing stamped from sheet metal in which the said 15 casing is utilized for the circulation of water, containing upper and lower water chambers and independent tube sections communicating therewith to provide a water circulation, the casing being also provided 20 with a front finishing bead, obviating the necessity of adding an additional finishing casing and thereby simplifying and improving the construction of the radiator and reducing the cost of manufacture.

25 Another object of the invention is to provide simple and novel means of securing the parts together, so as to permit of the ready removal and insertion of the independent tube sections.

30 A still further object is to provide means for temporarily closing the openings through which communication is established between the tube sections and the water chambers, so as to permit of the removal of one or more 35 of the tube sections without interfering with the use of the radiator.

Other objects and advantages of the invention will appear as the following description is read in connection with the accompanying drawings.

In the drawings:

Figure 1 is a sectional elevation of a radiator embodying the present invention;

45 Figure 2 is a section on the line 2—2 of Figure 1;

Figure 3 is an enlarged sectional view illustrating the manner of temporarily closing the openings in the water chambers;

50 Figure 4 is an enlarged detail sectional view illustrating the manner of temporarily closing the openings in the water chambers in a different form of the invention, the upper water chamber being shown in this figure; and

55 Figure 5 illustrates the manner of apply-

ing this closing means from the rear of the radiator.

In the usual construction of radiators, the radiator proper is ordinarily made of a single casting, which contains the upper and 60 lower water chambers connected together by the water circulating tubes. In this form of radiator it is necessary to make the casting of considerable thickness in order to secure proper strength and to prevent damage 65 to the casting when the core is removed. In order to present a neat and attractive appearance, it is necessary to use in connection with this casting, a cover or casing, thereby adding to the cost of manufacture and the 70 amount of material necessary to construct a radiator.

In order to overcome these and other disadvantages the present invention contemplates the provision of a casing stamped 75 from sheet metal, in which there is formed upper and lower water chambers connected together by independent tube sections or units, the novel manner of forming the casing simplifying its construction and materially reducing the cost of its manufacture.

In the accompanying drawings, the radiator shown comprises a casing which includes an upper water chamber 10 and a lower water chamber 11. The upper water 85 chamber is formed by stamping the front wall 12, the top wall 13 and the side wall 14 from a single piece of sheet metal, the latter forming means for connection with the lower water chamber as will be hereinafter described. The top wall 13 is provided with a suitable opening 15, which is surrounded by a nipple 16 for convenience in filling the radiator. The bottom wall 17 and the rear wall 18 of the upper chamber 10 is also 90 formed of a single piece of sheet metal stamped into the proper shape and having its edges secured to the rear and bottom edges of the top and front walls respectively, by brazing or other suitable means. The 95 bottom wall 17 is provided with a tubular extension 19 for connection in the ordinary manner with the water circulating system of an engine.

The lower water chamber has its top wall 105 20, its bottom wall 21 and its rear wall 22 stamped from a single piece of sheet metal, while the front wall 23 is separately formed and brazed or otherwise secured to the top and bottom walls.

The water circulating tubes 24 are arranged in independent tube sections and include upper water headers 25 and lower water headers 26, which are adapted to communicate through openings 27 and 28 formed respectively in the opposed walls of the upper and lower water chambers, these openings being provided with suitable gaskets 29 to prevent leakage.

- 10 In assembling the radiator, the independent tube sections are connected with the top water chamber and the bottom water chamber is then adjusted upon the opposite ends of these sections, this chamber being held in position through the medium of screws or bolts 30, provided at each end of the bottom water chamber, these screws passing through a metal block 31, brazed to each of the side walls of the casing, this last 15 mentioned block being provided with an offset 32 to provide edging flanges by means of which the radiator may be secured upon the frame of the vehicle.

20 As will be seen from the foregoing description and the accompanying drawings, each of the independent tube sections is removable and the radiator may be used after the removal of one or more of these sections, the openings provided in the water chambers 25 being temporarily closed by suitable means, one of which is illustrated in Figure 3. This consists of a compressible block 33, which is positioned upon the shank of a T-bolt 34. Also positioned upon the shank 25 of this bolt is a disk 35 and a clamping nut 36. By reference to Figure 3 it will be seen that the bolt 34 may have its head inserted through any one of the openings in the water chambers and the compressible block 33 30 positioned against the flange, the said block being securely held in such position by adjusting the nut 36.

35 In Figure 4 there is illustrated a modified form of this feature of the invention, the same being shown applied to the radiator of different construction, such as is illustrated in one of my pending applications. In this form of the invention there is provided a sleeve 37, one end of which is suitably secured within an opening 38 in the front wall of the water chamber. This sleeve is provided with a compressible lining 39 having an opening extending therethrough for the passage of the shank of a bolt 40, the said 40 shank being of slightly greater diameter than the opening 41 in the compressible lining 39. Secured upon the head 42 of the bolt 40 is a compressible member 43, which is adapted for insertion within the opening 44 through which communication is established between the water chamber and the water circulating tubes. The bolt 40 is provided with a reduced threaded extension 45 for engagement with the threaded socket 46 45 of a key 47.

When it is desired to close the opening 44 after the removal of a tube section, the bolt 40 is moved inwardly to engage the compressible member 43 with the opening 44 in the manner shown in Figure 4. The compressible nut of the lining 39 serves to securely hold the member in this position. When it is desired to remove the member 43 from the opening 44 for the purpose of re-establishing communication between the water chamber and the independent tube sections, the key 47 is inserted within the sleeve and engaged with the threaded end of the reduced portion 45 of the bolt, the opening 41 at the outer end of the compressible lining being surrounded by a metal sleeve 48 to permit of the ready insertion and removal of the key.

50 In the construction shown in Figure 5, the operation is the same, the difference being that the closing device is inserted from the rear of the radiator, the sleeve 49 being secured around an opening 50 provided in the rear wall of the water header 51 of each of the independent tube sections. This sleeve 49 carries a compressible member 52, within which operates a bolt 53 carrying a compressible head 54, which is adapted to engage the opening 55 through which communication is established between the water chamber and the header 51. The bolt 53 is withdrawn to open communication by engaging the key 47 with the threaded end 56 of the bolt 53.

55 It is believed that from the foregoing description taken in connection with the accompanying drawings, the construction and advantages will be apparent. The right is reserved to make such changes in the form and proportion thereof as will fall within the scope of the appended claims.

60 Having described the invention, what is claimed is:—

1. A radiator for internal combustion engines embodying a casing and comprising an upper water chamber formed of top and front walls and depending side walls made from a single piece of sheet metal, bottom and rear walls made from a single piece of sheet metal and secured to the top and front walls, a lower water chamber made from sheet metal, means for securing the lower water chamber to the depending side walls of the upper water chamber and water circulating tubes connecting said chambers.

65 2. A radiator for internal combustion engines embodying a casing and comprising an upper water chamber formed of top and front walls and depending side walls, bottom and rear walls secured to the top and front walls, a lower water chamber, means for securing the lower water chamber to the depending side walls of the upper water chamber, removably independent water tube sections, water headers for each end of said

sections, said headers having openings therein for register with openings in the upper and lower water chambers and closure elements for temporarily closing the openings 5 in the water chambers after the removal of a tube section and means for removably holding the closure elements in position.

3. A radiator for internal combustion engines embodying a casing and comprising 10 an upper water chamber formed of top and front walls and depending side walls, bottom and rear walls secured to the top and front walls, a lower water chamber, means for securing the lower water chamber to the

depending side walls of the upper water 15 chamber, removably independent water tube sections, water headers for each end of said sections, said headers having openings therein for register with openings in the upper and lower water chambers, a compressible 20 member adapted for engagement with the openings of the water chambers for closing the latter after the removal of a tube section and means for removably holding the compressible member in position. 25

In testimony whereof, I affix my signature.

JACOB B. BEAM.
